(57) **CLAIM**

The ornamental design for an avocado tool for slicing, pit removing, and scooping, as shown and described.

DESCRIPTION

FIG. 1 is a top perspective view of an avocado tool for slicing, pit removing, and scooping showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a bottom perspective view of the cutter in opening position.

The broken line representations in the figures show unclaimed environment, and thus form no part of the claimed design.
